CLAIM

The ornamental design for an oil drain receptacle attachment, as shown and described.

DESCRIPTION

FIG. 1 is an exploded view of the present invention that is an oil drain receptacle attachment.

FIG. 2 is a top perspective view of the present invention that is an oil drain receptacle attachment in an open configuration.

FIG. 3 is a front view of the present invention displaying an oil drain receptacle attachment in an open configuration, the rear view being a mirror image thereof.

FIG. 4 is a right-side view of the present invention displaying an oil drain receptacle attachment in an open configuration, the left side view being a mirror image thereof.

FIG. 5 is a front view of the present invention displaying an oil drain receptacle attachment in a closed configuration.

FIG. 6 is a top view of the present invention that is an oil drain receptacle attachment; and,

FIG. 7 is a bottom view of the present invention that is an oil drain receptacle attachment.

The broken lines shown in FIG. 7 illustrate portions of the oil drain receptacle attachment that form no part of the claim.
